CONVEYER

Henry A. Wise Wood, New York, N. Y., assignor to Wood Newspaper Machinery Corporation, New York, N. Y., a Corporation of Virginia

Application October 2, 1929. Serial No. 396,826

3 Claims. (Cl. 198—69)

This invention relates to the feeding of tails cut from stereotype plates and imperfect plates into the melting pot of a stereotype plate casting machine.

The principal objects of the invention are to provide a conveyer for this purpose, in which the tails, imperfect plates, pigs, or scraps of metal will not work off the conveyer on either side; to provide a conveyer with positive means for preventing the dislodgment of the objects on the conveyer from one edge, and with a peculiar construction for preventing the same thing happening on the other edge; and also to provide for tightening and loosening the chains of the conveyer.

Other objects and advantages of the invention will appear hereinafter.

Reference is to be had to the accompanying drawings, in which

Fig. 1 is a plan of a preferred form of this invention, shown double;

Fig. 2 is a side view of the same looking in the direction of the arrow 2 in Fig. 1;

Fig. 3 is a plan of the junction between the two conveyers and the driving means therefor as shown in Fig. 1, but on enlarged scale;

Fig. 4 is a side view, taken in the direction of the arrow 4 in Fig. 3;

Fig. 5 is a sectional view of the conveyer and operating means, taken on the line 5—5 of Fig. 1;

Fig. 6 is a side view of one of the conveyers, looking in the direction of the arrow 6 in Fig. 1, and showing the adjusting means in section;

Fig. 7 is a plan of the same; and

Fig. 8 is an end view of one of the conveyers looking in the direction of the arrow 8 in Fig. 1.

The invention is shown as applied for the purpose of supplying metal to a melting pot 10 and is illustrated in double form, so that the tails

cut from plates on two casting machines or units can be introduced into the same melting pot by these conveyers in a convenient manner. It will

be understood that the melting pot is intended to supply the metal to the two casting machines.

This invention does not relate to any other part of the casting machine and therefore the drawings do not illustrate any part of the casting machine.

On a bracket carried by this machine, or in any other convenient position, is a motor 12, which, through sprockets 13, drives a shaft 14. On this shaft is a worm 15 driving a worm gear 16 on a shaft 17 which is located longitudinally with respect to the oblong melting pot and preferably along one side edge thereof and support-

ed by a bracket 18 bolted to the upper side edge of the melting pot.

As stated, a double machine is shown, although the invention can be carried out in substantially the same manner with only a single conveyer, whether it receives metal in a solid state from one casting machine or two. But in the present illustration, the shaft 17 is provided with two bevel gears or pinions 19, each one meshing with a bevel gear 20 located on shafts 21. These shafts 21 are located at a considerable angle to the shaft 17. These two shafts 21 therefore may be located at an angle of about 90 degrees apart, or at any other convenient angle, and they are supported in bearings 22 carried by a frame 23 which is supported in inclined position, as indicated in Fig. 8, on uprights 24.

The two driving shafts 21 are located over a side edge of the melting pot. At opposite ends of the two frames 23 are similar shafts carrying the other end of the device. On each of these four shafts 21 are located a pair of sprockets 25 which mesh with sockets 26 extending inwardly from a series of slats 27 constituting two conveyers. Each shaft at the opposite end is also provided with idler sprockets for the same purpose, but the sprockets 25 of course are keyed to the shaft 21, so that the conveyer is positively driven. This conveyer being composed of cross-slats constitutes a moving platform in each case which moves out over the melting pot and deposits all loose objects on it directly into the melting pot and into the body of molten metal therein. It will be observed, from the position of the two conveyers shown, that they are adapted to receive the severed tails and imperfect plates from two units of an automatic stereotype casting plant and deliver all of them to the same melting pot.

The purpose of slanting the conveyer is to prevent the displacement of the tails and plates thereon over the upper edge of the conveyer. By having this slanting arrangement, the tails and plates gradually work down to the lower edge and there is no danger of their being discharged over the higher edge.

At the lower edge is a buffer plate 29 which may be integral with the frame 23 or secured thereto in any desired way, which extends clear out into a position over the molten metal in the melting pot 10, and thus the plates and tails will be moved along substantially in contact with this buffer plate and discharged in a position near the middle of the melting pot.

- For the purpose of adjusting the tautness of the conveyers, the shaft 21, which constitutes the idler shaft to support the idle end of each endless apron, is supported in a pair of brackets 32 having slots 33 and adapted to be tightened by screw 34 for each bracket. The brackets are secured in position by bolts 35 passing through the slots 33 and into the solid part of the frame 23.
- 10 It will be obvious that the adjustment of the endless aprons or conveyers for taking up any slack in them is conveniently reached from opposite sides of the conveyers. It will be seen also that each conveyer is so constructed with a minimum of expense; that the plates and tails will move along one edge thereof and be deposited out into the middle of the melting pot, where molten metal will not be likely to splash up on the machinery, and that two conveyers 20 are shown as arranged for receiving tails and plates from the two casting machines spaced apart as previously stated.

Although I have illustrated and described only a single form of the invention, I am aware 25 of the fact that changes can be made therein by any person skilled in the art without departing from the scope of the invention as expressed in the claims. Therefore I do not wish to be limited to the exact form shown, but what I do 30 claim is:—

1. A conveyer for the purpose described, comprising an endless apron and means for operating it, a frame on which said apron is located inclined transversely so that objects on the con-

veyer will not have any tendency to be discharged over the high edge thereof, and a buffer plate along the low edge for insuring the delivery of the objects on the conveyer from a point at the end of said low edge.

2. In a conveying device for the purpose described, the combination with a receiver, a shaft located on the edge of the receiver and longitudinally positioned with respect to said edge, and gearing on said shaft at opposite ends, of a pair of driving shafts located at a material incline from each other and driven from the first named shaft by said gearing, and a pair of conveyers for dropping objects into the receiver connected with said last named shafts to be driven thereby.

3. In a conveying device for the purpose described, the combination with a shaft located on the edge of a receiver and longitudinally positioned with respect to said edge, and bevelled gearing on said shaft at opposite ends, of a pair of driving shafts located at a material incline from each other and driven from the first named shaft by said bevelled gearing, a pair of conveyers for dropping objects into the receiver connected with said last-named shafts to be driven thereby, said conveyers being transversely inclined so that objects on the conveyer will not have any tendency to be discharged over the high edge thereof, and a buffer plate along the lower edge for insuring the delivery of the objects on the conveyer from a point at the end of said lower edge.
